UNITED STATES PATENT OFFICE.

GEORGE HENRY SCHOENTHALER, OF ROCHESTER, NEW YORK, ASSIGNOR, BY MESNE ASSIGNMENTS, TO LOCKE INSULATOR CORPORATION, OF BALTIMORE, MARYLAND, A CORPORATION OF MARYLAND.

INSULATOR.

Application filed April 14, 1919. Serial No. 289,793.

The invention broadly considered relates to insulators and more particularly to insulators of the suspension type, in which one insulator unit is suspended from a rigid support or a similar insulator unit.

5 The main object of my invention, generally stated, is to provide novel means for connecting an insulator to the metallic elements which together with the insulator 10 form what may be termed an insulator unit.

There are other objects of my invention as will more fully appear from the detailed description thereof when taken in connection with the accompanying drawings, wherein I 15 have illustrated certain embodiments of the invention and in which:

Figure 1 is a vertical cross section through an insulator unit, showing the invention applied thereto;

20 Figure 2 is a side elevation of the skeleton cap;

Figure 3 is a top plan view of the cap illustrated in Figure 2;

Figure 4 is a section taken on line 4—4 of 25 Figure 1;

Figure 5 is a section taken on line 5—5 of Figure 1.

Throughout the specifications and drawings, like parts are designated by like reference characters.

30 Referring to the drawings, which it will be understood are merely illustrative of the underlying features of the invention, the numeral 1 designates an insulator of the suspension type, 2 the neck or stem and 3 the flaring skirt which curves outwardly and downwardly from the neck or stem 2. Adjacent the juncture of the said neck and skirt portions of the insulator, there is preferably provided in the said neck 2 an undercut groove or recess 4.

Surrounding the projecting neck 2 of said insulator there is provided a bell-shaped cap 5 which may and preferably does comprise 45 an upwardly flaring ring 6 having an undercut circumferentially extending groove 6^a on the under or inner side thereof. The said cap is provided with means for suitably connecting the same to an insulator support or 50 companion insulator, the said means may, for example, comprise a plurality of straps 7 preferably four in number and a pair of pivot ears 8—8, which may, for convenience,

be formed integral with one of said straps 7. The said pivot ears 8 are each provided with 55 an aperture 9 for the reception of a bolt or like fastening means.

Within the said stem 2 and opening from the under side of the insulator is a cylindrical recess 10, this recess is preferably 60 widened out or increased in diameter adjacent the upper end to provide a shouldered enlargement 11. Extending within the said recess 10 there is provided an eye bolt or an equivalent device. This bolt may, for convenience be formed as a U-shaped member 12, each leg 13, thereof being split and separated for a portion of its length, as is clearly seen in Figures 1 and 4. Adjacent the upper ends of the said legs 13 they are each 65 provided on their exterior faces with outwardly extending lips or flanges 14 and may and preferably are provided on their interior faces with outwardly flaring wedge faces 14^a, the object and purpose of which will 70 hereinafter be more fully described.

To securely and strongly unite the cap and bolt to the insulator body, I employ a metal having a comparatively low melting point and possessing when cold both strength and 80 resiliency. I prefer to use Babbitt metal, an alloy composed of copper, tin and antimony, as this metal possesses the desirable qualities set forth above, but it is to be understood that in the broad aspect of my invention I 85 do not limit myself to this metal as other metal applied in a molten state may be employed advantageously as the connecting means between the parts of an insulator unit.

In carrying out my invention, I may pour 90 the molten metal between the oppositely disposed grooves 4 and 6^a in the insulator body and cap respectively so that the metal when cold will fill the said grooves, as clearly shown in Figs. 1 and 4, appropriate means, such as an asbestos gasket being temporarily provided beneath the cap to prevent the escape of this molten metal. The asbestos gasket also serves to space the hard metal of the cap from the skirt of the porcelain body portion. The metal filler may be formed 95 as a split ring 15, as shown in Fig. 4.

The eye bolt which is received within the recess in the insulator body is also preferably connected to the insulator by means 100 of metal introduced in a molten state. To

assemble the eye bolt 12 with the insulator body, the latter is inverted and an asbestos gasket 18 inserted within the said recess, a small wedge block 19 of cruciform outline is then placed in the bottom of the recess and the eye bolt inserted, the wedging faces 14^a on the legs of the latter are adapted to engage the correspondingly formed wedging faces on the wedge 19 to separate the 10 said legs so that the outwardly projecting lips 14 thereof extend within the chamber 11 of the recess 10.

While the eye bolt 12 is maintained in this position, the molten metal is poured 15 into the recess filling in the intervening spaces between the walls of the recess and the legs of the eye bolt, as clearly shown at 20 in Fig. 5.

The insulator body is preferably so constructed that the adjacent portions of the grooves 4 and 11 hereinbefore described extend substantially in the same direction and are slightly spaced laterally from the same vertical plane, in other words, the adjacent 25 portions of the said annular grooves are so arranged that the strains borne by the insulator body due to the pull of the cap and bolt in opposite directions, are largely, if not entirely, compressive instead of tensional, thereby affording a unit working at a smaller percentage of its ultimate mechanical and electrical strength than those units now commonly employed. The metallic connector is also placed under compressive 30 strains by employing the construction herein described and moreover any slight expansion or contraction of the metallic connector will be taken care of by the ability of the metal parts to rise or fall with reference to 35 the insulator body, the compressibility of the asbestos gasket hereinbefore described permitting the necessary movement of the eye bolt. As will be noted from Figure 1, the cap is normally slightly spaced from the 40 exterior surface of the neck of the insulator and this slight spacing, together with the inclined shoulders of the groove 6^a permit of the slight movement of the cap to compensate for the expansion or contraction of the 45 metallic connector.

The ability of the cap and eye bolt to move and thus compensate for the expansion of the metallic connector eliminates all stresses caused by the expansion of the parts and

thereby avoids all damage to the insulator 55 body.

It will be understood that while my novel form of connecting means may be advantageously employed in connection with the solid or imperforate form of cap that I 60 prefer to use the same in combination with the skeleton form of cap, as shown in Figs. 1 to 3 inclusive, since by this combination I obtain a better balance of the electrostatic field than is possible with the imperforate form of cap referred to and in addition by reason of the skeleton form I am enabled to readily inspect the assembly of 65 the insulator and cap.

Owing to the process of manufacture insulator bodies are subject to slight irregularities in the surface and to slight distortion and by using molten metal as the connecting means between the insulator body and the metallic members, I am enabled to 70 make a uniform and permanent connection and bearing between the said body and the metallic parts since the fluid metal will flow into the irregularities and will follow the 75 contour of the insulator body and metal 80 parts.

Having now described my invention, although it is to be understood that the terms employed are to be taken in their descriptive and not their limited sense, what I claim and 85 desire to secure by Letters Patent is:

1. In an insulator, a dielectric body having an upstanding neck portion formed with a downwardly opening recess with an undercut portion, a pin located within the recess, 90 the pin being of substantial U-shape and having legs split and spread, means within the recess for expanding the pin at the ends of the split portions thereof, and means for embedding the pin within the recess. 95

2. In an insulator, a dielectric body having a stem portion formed at its underside with a recess and an undercut groove within the recess, a pin extending within the recess and including a pair of leg portions 100 each split in sections with the sections spaced apart, a wedge member located within the recess and engaging against the sections of both legs of the pin for expanding the pin into said groove, and means for embedding 105 the pin within the recess.

In testimony whereof I affix my signature.
GEORGE HENRY SCHOENTHALER.
